United States Patent Office

Des. 178,554
Patented Aug. 14, 1956

178,554

METAL ANODE

Joe A. Stone, Chicago, Ill.

Application March 23, 1955, Serial No. 35,171

Term of patent 14 years

(Cl. D26—1)

Fig. 1.

Fig. 2.

Figure 1 is a perspective view of the metal anode embodying my new design;

Figure 2 is an end elevational view showing the end at the right hand side of Figure 1.

I claim:

The ornamental design for a metal anode, substantially as shown.
